(57) **CLAIM**

The ornamental design for a composter, as shown and described.

DESCRIPTION

FIG. 1 is a rear, left and top perspective view of a composter, showing our design.

FIG. 2 is a front, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a cross-sectional view viewed from a view line 9-9 as indicated in FIG. 6.

The broken lines depict portions of the composter that form no part of the claimed design.
